UNITED STATES PATENT OFFICE

165,804

DUMP TRAILER

Herbert H. Turner, Boscobel, Wis.

Application April 7, 1949, Serial No. 1,849

Term of patent 14 years

(Cl. D14—3)

To all whom it may concern:

Be it known that I, Herbert H. Turner, a citizen of the United States, residing at Boscobel, in the county of Grant and State of Wisconsin, have invented a new, original, and ornamental Design for a Dump Trailer, of which the following is a specification, reference being had to the accompanying drawings, forming part thereof, in which:

The characteristic features of my design reside in the portions shown by means of full lines in the drawing.

I claim:

The ornamental design for a dump trailer, as shown and described.

HERBERT H. TURNER.
